United States Patent

Des. 236,875
Patented Sept. 23, 1975

236,875

DOOR KNOCKER RING

Raymond U. H. Tegner, Lodi, Wis., assignor to
Amerock Corporation, Rockford, Ill.

Filed Jan. 4, 1974, Ser. No. 430,939

Term of patent 14 years

Int. Cl. D8—09

U.S. Cl. D8—177

FIG. 1 is a front view of a door knocker ring incorporating my new design.

FIG. 2 is a side view of the door knocker as seen from the right of FIG. 1.

FIG. 3 is a bottom view of the door knocker.

FIG. 4 is a back view of the door knocker.

FIG. 5 is a sectional view taken along the line 5—5 in FIG. 1.

I claim:

The ornamental design for a door knocker ring, as shown.
